(57) **CLAIM**

The ornamental design for a seat, as shown and described.

DESCRIPTION

FIG. 1 is a three-quarter perspective view of a seat in accordance with the present invention;

FIG. 2 is a front elevational view of the present invention;
FIG. 3 is a right side elevational view of the present invention, the left side elevational view being a mirror image thereof; and,

FIG. 4 is a top-front perspective view of the present invention.

It will be understood that the bottom plan view and rear elevational view are not illustrated as they form no part of the claimed design, and that the broken lines shown in FIGS. 1 and 3 illustrate structure associated with the present invention but also form no part of the claimed design.
